[57] **CLAIM**

The ornamental design for a light socket mounted remote controlled light switch, as shown and described.

DESCRIPTION

FIG. 1 is a front elevational view of a light socket mounted remote controlled light switch showing my new design, the rear elevational view being a mirror image.

FIG. 2 is a right side elevational view thereof, the left side elevational view being a mirror image.

FIG. 3 is a top plan view thereof.

FIG. 4 is a bottom plan view thereof.

FIG. 5 is a perspective view thereof.
